UNITED STATES PATENT OFFICE.

CHARLES LEWIS WAGANDT, OF BALTIMORE, MARYLAND, ASSIGNOR TO
KEEN & HAGERTY, OF SAME PLACE.

CHILD'S TRAY.

SPECIFICATION forming part of Letters Patent No. 402,788, dated May 7, 1889.

Application filed December 12, 1888. Serial No. 298,385. (No model.)

To all whom it may concern:

Be it known that I, CHARLES LEWIS WAGANDT, a citizen of the United States, residing in the city of Baltimore and State of Maryland, have invented certain new and useful Improvements in Children's Trays; and I do declare the following to be a full, clear, and exact description of the invention, such as will enable others skilled in the art to which it appertains to make and use the same.

My invention relates to those trays which are designed for the use of young children at the table, and has for its object the production of a tray of improved construction which will be better adapted to holding dishes and preventing the spilling and dropping of food, which will protect the garments of the child, which cannot be displaced from its proper position at the edge of the table so long as the child is situated before it, and which when not in use may have its securing devices folded down upon its surface to enable it to be conveniently packed or laid aside.

According to my invention the front portion 25 of the tray projects a considerable distance over the edge of the table, and is formed with a cut-out portion, which recess fits the body of the child, the portions of the tray at each side of the recess projecting forward and past the position ordinarily occupied by the infant's body. The inner sides of the recess, therefore, constitute what may be termed "supporting-walls," extending forward at substantially right angles to the edge of the table, 35 and are adapted to support the child in an upright position. It further results from this construction that portions of the tray, when in use, are situated at each side of the child and extend forward for such distance 40 as to render it almost impossible for dishes or articles of food to be dropped upon the floor.

My invention further consists in certain parts and combinations thereof, hereinafter 45 particularly set forth.

In order to make my invention more clearly understood, I have shown in the accompanying drawings means for carrying the same into effect.

50 In said drawings, Figure 1 is a perspective

view of a child's tray embodying my improvements. Fig. 2 is a front view of the same. Fig. 3 is a bottom plan view, illustrating the manner of folding the securing devices when the tray is not in use. Fig. 4 is a sectional view on line 4-4, Fig. 2.

Referring to the drawings, A is the body of the tray, which is provided with a surrounding rim, a, of suitable height. The material of the tray may be tin suitably japanned or 60 ornamented.

At B is indicated the space formed by cutting out the front edge of the tray so as to leave two forwardly-projecting portions, A' 65 A', which will be adapted, in use, when the body of the child is situated in the space B, to extend forward for a considerable distance and to be situated at each side of the user.

The tray is designed to be so placed upon the table that the front edge of the latter will 70 be substantially in line with the inner side of space B, and to insure such placing of the tray, and also to prevent its being tipped up and its contents spilled by downward pressure upon the projections A', I have provided 75 suitable securing devices for regulating the position of the tray and holding the rear edge of the tray down upon the table. In this instance said devices consist of strong spring fingers or clasps of wire or other suitable material. In the construction shown the tray is provided upon the outer and under sides of the rim a with sleeves b, soldered to said rim. The spring-clasps, the securing-arms of which are indicated at C, are provided also 80 with vertical portions c² and arms or journals c, which are adapted to fit and turn within the sleeves b. The clasps are also provided with a bend or set-off, (shown at c'), by which the portions c² of the clasp are held 85 at sufficient distance from the journal or pivot c to clear the edge of the bottom of the tray and enable said clasps to be folded flat upon the bottom surface of the latter, as shown in Fig. 3. In placing the tray for use, the portions c² bear against the edge of the table and 90 insure the proper position of the tray, while the arms C bear against the under side of the table and hold down the rear portion of the tray and sustain the front portions, A' A'. 95 100

The securing devices or clasps are preferably made removable, the pivot *c* being adapted, in the construction shown, to be withdrawn from the sleeves *B*. When this has been done, it will be seen that, on account of the position of the sleeves *b*, there will be no projection of any kind upon the bottom of the tray and the trays will be well adapted to be packed one upon the other for shipment 10 without occupying much space and without danger of jamming or collapsing the sleeves.

I preferably form the rim of the tray where it bounds the rear side of the space *B* in such manner, as shown at *a'*, that it constitutes an 15 upward extension from the main portion of the rim and forms a protector or apron by which the garments of the child will be protected and food caught and deflected upon the tray, instead of being allowed to drop into 20 the lap or upon the floor.

A band around the child's body, or supports adapted to sustain the projections *A'A'* upon the arms of the child's chair, might be employed to prevent the tipping of the tray, instead of using, as in the illustration, holding 25 devices which engage the table.

I am aware that it has been heretofore proposed to construct waiters with a recess for the arm of the person carrying them, with a 30 view to prevent the accidental dropping of the waiters, and I do not wish to be understood as claiming anything contained in such a construction.

Having thus described my invention, what I claim is—

1. As an improved article of manufacture, a child's table-tray recessed upon its front side, as described, and having upon each side of such recess the forward projections, *A'*, the inner sides of which extend at substantially 40 right angles to the table and are adapted to fit the sides of the child and hold its body from sidewise movement, substantially as set forth.

2. As an improved article of manufacture, 45 a child's table-tray recessed upon its front side, as described, and having upon each side of such recess the forward projections, *A'*, the inner sides of which are situated at and are adapted to fit the sides of the child's body 50 and hold it from lateral movement, the tray being provided around said recess with the protector or apron *a'*, extending upward above the rim of the tray, as shown, and adapted to protect the clothing of the child and deflect 55 into the tray spilled articles of food, substantially as set forth.

In testimony whereof I affix my signature in the presence of two witnesses.

CHARLES LEWIS WAGANDT.
